UNITED STATES PATENT OFFICE.

MARY E. PHOEBUS AND MARGARET NATALIE PHOEBUS, OF BROOKLYN, NEW YORK.

DESIGN FOR A MEMORIAL BAND.

52,404.

Specification for Design.

Patented Sept. 10, 1918.

Application filed December 29, 1917. Serial No. 209,585. Term of patent 3½ years.

To all whom it may concern:

Be it known that MARY E. PHOEBUS and MARGARET NATALIE PHOEBUS, both citizens of the United States, residing at Brooklyn, in the county of Kings and State of New York, have invented a new, original, and ornamental Design for a Memorial Band, of which the following is a specification, reference being had to the accompanying drawing, forming part thereof.

The figure is a plan view of the memorial band, showing our new design with the ends broken away.

We claim:

The new original and ornamental design for a memorial band as shown, with the ends broken away.

MARY E. PHOEBUS.
M. NATALIE PHOEBUS.
